CLAIM

The ornamental design for a fluid connector, as shown and described.

DESCRIPTION

FIG. 1 is a perspective view of the fluid connector of the present design application; the break lines in the fluid connector body are shown to indicate that a specific length of fluid connector forms no part of the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The figures are lined for the color Red.

The broken line showing of portions of the fluid connector is included for the purpose of illustrating environment and forms no part of the claimed design.
